Primary Examiner — Jae Liang*Assistant Examiner* — Riya Salil Kamat(74) *Attorney, Agent, or Firm* — Morgan, Lewis & Bockius LLP(57) **CLAIM**

The ornamental design for a golf putting training tool as shown and described.

DESCRIPTION

FIG. 1 is a front perspective view of a golf putting training tool showing our new design;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines depict portions of the golf putting training tool that form no part of the claimed design.
